Specification for Design.

Patented Aug. 2, 1921.

Application filed April 30, 1921. Serial No. 465,841. Term of patent 14 years.

To all whom it may concern:

Be it known that I, ELMER N. JOHA, a citizen of the United States, residing at Milwaukee, in the county of Milwaukee and State of Wisconsin, have invented a new, original, and ornamental Design for Knitted Caps, of which the following is a specification, reference being had to the accompanying drawing, forming part thereof.

Figure 1 is a side elevation of a knitted cap embodying my new design, with the band turned up.

Fig. 2 is a side elevation with the band turned down.

Fig. 3 is a front elevation with the band turned up.

I claim:

The ornamental design for a knitted cap, as shown.

ELMER N. JOHA.
